UNITED STATES PATENT OFFICE.

EDWIN C. ROYER AND BERNARD J. BOYLE, OF PHILADELPHIA, PENNSYLVANIA.

CLENCH OR EXPANSION NAIL.

1,336,162.

Specification of Letters Patent. Patented Apr. 6, 1920.

Application filed September 20, 1919. Serial No. 325,113.

To all whom it may concern:

Be it known that we, EDWIN C. ROYER and BERNARD J. BOYLE, citizens of the United States, residing at Philadelphia, county of Philadelphia, and State of Pennsylvania, have invented certain new and useful Improvements in Clench or Expansion Nails, of which the following is a specification.

10 One object of our invention is to provide an improved clench or expansion nail which can be used for quickly securing pieces of metal or other material together or which can be used as a cotter pin or ordinary expansion nail.

Another object is to make our improved clench or expansion nail of such construction that when placed in position it will present a smooth continuous head free of any 20 objectionable projections.

A still further object is to make our invention of a simple and durable construction and so that it can be quickly and cheaply manufactured.

25 These objects, and other advantageous ends which will be described hereinafter, we attain in the following manner, reference being had to the accompanying drawings in which—

30 Figure 1 is a perspective view of our improved clench or expansion nail,

Fig. 2 is a view showing how our improved nail can be inserted through registering holes of two pieces of metal, and

35 Fig. 3 shows a view of similar nature to Fig. 2, the nail having been struck in such manner as to spread the inner portion thereof to securely bind said pieces of metal together.

40 Referring to the drawings, our improved nail consists of a continuous piece of strip metal which is bent to provide a looped head 4. The portions leading from the head are folded upon themselves, as shown at 5, to 45 produce tines or prongs; the folding being such that the end portions 6 are positioned between the other portions 7, said end portions extending into the looped head 4 and are normally positioned within a recess 8 included in said looped head 4. The looped head 4 provides shoulder portions 9 which are adapted to engage the outer surface of any material through which the nail is inserted, such for example as the outer surface 55 of the piece of metal 11, as shown in Figs. 2 and 3. It will be noted that the

recess 8 is formed by a hump or projection 12, which is centrally located in alignment with the portions 6. Thus when the nail is inserted through the holes 13 and 14 of the pieces of metal 11 and 15, as shown in Fig. 2 and the head is struck by a hammer, the end portions 6 will be pushed longitudinally by engagement with the looped head 4 and in so doing will bend the portions 7, as shown in Fig. 3, to spread said portions 7 and thereby clamp the pieces of metal 11 and 15 together; it being further noted that the portions 6 will also assume a spread position.

By providing the continuous looped head 4, the extreme ends of the end portions 6 will always be positioned within the confines of the looped head 4 so that they will not project or be exposed when the nail is in securing position. Furthermore by providing the recess, the extreme ends of the portions 6 will be held in central alignment during the hammering action and therefore the tines or prongs will expand evenly in opposite directions. At the same time the recess 80 provides a comparatively great space between the hump portion 12 and the shoulder portion 9, so that the end portions 6 can be moved a sufficient distance inward to cause a wide expansion of the tines or prongs.

While we have described our invention as taking a particular form, it will be understood that the various parts of our invention may be changed without departing from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:—

1. A nail of the character described including a looped head and tines projecting therefrom, said tines being folded and having their end portions extending into said looped head; substantially as described.

2. A nail of the character described including a looped head and tines projecting therefrom, said tines being folded and having their end portions extending into said looped head, said looped head having a recess in alignment with said end portions; substantially as described.

3. A nail of the character described including a looped head and tines projecting

therefrom, said tines being folded and having their end portions extending into said looped head, said looped head having a recess in alinement with said end portions and 5 into which the ends of said end portions extend; substantially as described.

In testimony whereof we have signed our

names to this specification in the presence of two subscribing witnesses.

EDWIN C. ROYER.
BERNARD J. BOYLE.
